UNITED STATES PATENT OFFICE.

PETER SANTURELLO, OF COLUMBUS, OHIO.

HAIR WRAPPER.

Application filed September 8, 1927. Serial No. 218,338.

This invention relates to improvements in flexible wrappers of the type adapted for use in confining the hair in carrying out various processes of heat treating human hair, particularly the process known as the permanent wave.

In such treatments of the hair it is necessary to highly heat the same, but this must be done in a manner to avoid injuring the hair by excessive heating or without causing pain or discomfort to the patron. Ordinarily, in the attainment of this strands or tufts of hair are wrapped helically and tightly under tensile stress around a core or mandrel, and the hair is then surrounded by a wrapper or pad of a fabric material, saturated with a suitable chemical, and is then placed in an electric or other heater for the necessary application of heat to set the hair in the desired curled or waved form.

Prior wrappers or pads used in this process have given considerable difficulty in that unless the same are carefully applied to the hair and the ends of such wrappers sealed, the steam or vapors formed during the application of heat escape and are apt to burn the scalp of the patron and, again, unless such wrappers offer complete and effective protection to the hair there is an ever present likelihood of burning or overheating the hair with attendant injurious results.

It is, therefore, the object of the present invention to provide an improved and simplified form of wrapper or container which may be readily applied to the tufts or strands of hair wound upon the core or mandrel so that the hair will be completely encased by the wrapper for heat treatment thru an exterior source and in such manner as to minimize the likelihood of injury to the hair thru over-heating or injury to the scalp by the undue escape of steam or vapor formed in the wrapper during the heating process.

For a further understanding of the invention reference is to be had to the following description of the accompanying drawing, wherein:

Figure 1 is a plan view of the wrapper blank comprising the present invention.

Figure 2 is a sectional view taken on the plane indicated by the line 2—2 Figure 1.

Figure 3 is a similar view on the line 3—3 of Figure 1.

Figure 4 is a perspective view showing the wrapper in a position to be initially applied

to a wound tuft of hair carried by a core or mandrel.

Figure 5 is a vertical sectional view showing the wrapper in its finally applied position around the hair and within the heating chamber of a heating unit.

Referring more particularly to the drawing the numeral 1 designates the improved wrapper comprising the present invention. 65 The wrapper consists of a blank of fabric material such as, for example, muslin, linen or the like, and is formed to include substantially rectangular pad and wrapping sections 2 and 3 respectively. The fabric is 70 doubled upon itself so that each section will include adjacent inner and outer layers 4 and 5 respectively, and the marginal edges of these sections are stitched as at 6 so that the inner and outer layers will be held in 75 fixed and proper order.

Between the layers of the pad section there is interposed a flat pad 7 of cotton, felt or other absorbent material, and, if desired, in particular, this pad is moistened or 80 saturated with a chemical solution to facilitate the hair waving process.

The wrapping section has applied and secured to the outer layer thereof, a paper sheet 8 which extends over the full area of 85 the wrapping section and is held in connection therewith by the stitching 6. One end of the wrapping section has secured thereto by means of the stitching 6 a sheet of metallic foil which is indicated by the 90 numeral 9. This sheet extends beyond the adjacent marginal edges of the sections 2 and 3 and is provided with a lower edge portion which is cut on a bias as indicated by numeral 10. It will be observed that the 95 wrapping section is slightly longer than the pad section, as is clearly indicated in Figures 2 and 4.

In practice, a strand or tuft of hair 11 is helically curled and wrapped about a core or 100 mandrel 12 with the hair under tension. When in this condition and, as shown in Figure 4, the wrapper is applied to the hair so as to completely cover and protect the same. The pad section is first applied and wrapped around the hair in order to place the chemical containing pad in close contact with the hair. Further wrapping permits the section 3 to be tightly positioned around the hair so as to completely enclose and protect the same. The ends of the wrapper are 110 then closed or sealed by helically twisting

the sheet of metallic foil 9 around the ends of the core 12, and since the foil possesses deformable properties the same will closely adhere to the core to seal that end of the 5 wrapper. By off-setting or lengthening the opposite end of the wrapping section with respect to the pad section, the end of the wrapper opposite to the foil bearing end may be readily bunched as indicated in Figure 5, 10 permitting of the application thereto of a clamp 13 which operates to seal that end of the wrapper with which it is engaged. The wrapped and protected hair is then placed 15 into the heating chamber of a heater 14 which, as shown in Figure 5, may be of electrical type which generates sufficient temperature to bake and set the hair contained within the wrapper. By reference to Figure 5, it will be noted that when the wrapper 20 assumes its applied position the paper sheet 8 will completely cover the exterior surface thereof with the exception of the foil 9. This paper sheet offers considerable protection 25 to the hair and specifically prevents overheating or burning thereof. In addition, the paper serves to prevent the escape of steam or vapor from the wrapper during the heating operation, thru confining the heat within the wrapper and preventing its 30 escaping into atmosphere or contacting with the scalp of the patron.

In view of the foregoing, it will be seen that the present invention provides a simple and improved wrapper or container which 35 can be manufactured at a relative low cost and which can be readily adapted for the purpose to which it is applied with the use of but ordinary skill on the part of the operator. While I have described what is considered

the preferred form of the invention, nevertheless, it will be understood that I do not limit myself to the precise details of the construction illustrated and described, but reserve the right to employ such variation or modification thereof that may be said to fall 45 fairly in the scope of the following claims.

What is claimed is:

1. A wrapper for the purpose set forth, comprising a fabric body of substantially rectangular form, said body being formed to 50 include pad and wrapping sections, a paper sheet covering the outer side of the wrapping section, a chemical receiving pad carried by the pad section, and a strip of deformable metal foil connected with and projecting from one of the end edges of the 55 wrapping section.

2. A wrapper for the purpose set forth comprising a fabric body of substantially rectangular form, said body being formed to 60 include pad and wrapping sections, one end of wrapping section being arranged to project beyond the complementary end of the pad section, the other end of said sections terminating substantially evenly, and a strip of 65 metal foil secured to and projecting beyond the edge of the wrapping section which terminates evenly with the corresponding edge of the pad section.

3. A wrapper for the purpose set forth, 70 comprising a fabric body of substantially rectangular form shaped to include pad and wrapping areas, a sheet of paper covering one side of said wrapping area, and a strip 75 of deformable material projecting from one end of said wrapping area.

In testimony whereof I affix my signature
PETER SANTURELLO.
